CONTAINER

Edwin Sherman, Alton, Ill., assignor to Ralph E. Marshall, Alton, Ill.

Application March 6, 1935, Serial No. 9,548

7 Claims. (Cl. 206—41)

This invention pertains to containers, and more particularly to containers of the type adapted for holding loose materials such as pipe tobacco.

One of the objects of this invention is to provide a container which may be constructed of stiff sheet material, such as sheet metal, and which may be formed in flat shape so as to fit the pocket, and which may be expandable so as to render it easy to insert the pipe for filling.

10 Another object is to provide such a container, which may be constructed of a single piece of sheet material and which may be rendered tight against leakage of the material therefrom.

Another object is to provide such a container, together with a liner therefor, which liner will render the container tight to hold the material.

Another object is to provide such a container with an enclosure adapted to retain the same in closed or collapsed position, together with means whereby the container is automatically expanded when the cover is opened.

Further objects will appear from the following description, taken in connection with the accompanying drawings in which

25 Figure 1 is a side view of a container embodying this invention;

Figure 2 is a section on line 2—2 of Figure 1;

Figure 3 is a perspective view of the container in expanded position;

30 Figure 4 is a detail showing a flat bottom construction;

Figure 5 is a similar detail showing a hinged bottom construction;

Figure 6 is a view of the sheet blank from which 35 the container is constructed, before folding to shape;

Figure 7 is a perspective view of the liner partly folded; and

40 Figure 8 is a view of the liner blank laid out for folding.

Referring to the drawings, Figure 6 shows the blank which is marked off to provide a front side 1, a rear side 2, and end portions 3 and 4. Between the side portions 1 and 2, is a bottom portion 5.

45 As shown in Figure 3, the blank is folded up so as to form the container of the shape shown in that figure. The end portions 3 and 4 are folded towards each other so as to overlap to form the container. A separate cover 6 is hinged at 7 to the rear portion 2 and provided with a catch 8 engageable with a detent 9 on the front side 1. The bottom portion may be formed round as shown in Figure 3, or flat as in Figure 4. When

formed flat, it provides a bottom upon which the container may stand up. The cover 6 is so arranged that when the container is closed or collapsed by moving the side portions 1 and 2 together, as far as permitted by the end portions 3, the cover will overlap the upper edge of the part 1 and the catch 8 will engage the detent 9. In this position the cover will retain the container in collapsed position against the tendency to spring open. The bottom portion 5 is so formed that the resiliency of the material tends to spring the container into expanded position. Accordingly, when the cover 6 is opened, this resiliency causes the automatic expansion of the container.

10 In accordance with the construction indicated in Figure 5, the container may be formed of two pieces hinged together at 10. A spring 11 may be provided to cause the parts 1 and 2 to spring apart when the cover 6 is opened.

15 It will be noted that when the container is completely formed, the end portions 3 and 4 are in closely adjacent relation to each other and the bottom portion 5 so that the container has substantially closed joints which are tight against leakage of the loose material therefrom. This 20 construction is obtained in spite of the fact that there are no connections between the edge portions of the sheet at the ends 3 and 4.

25 A liner for the casing is provided as illustrated in Figures 7 and 8. The liner is cut to the form shown in Figure 8 and creased for folding as indicated by the lines shown in that figure. A series of bellows creases 12 run longitudinally along the middle of the sheet. The corners are creased for folding as indicated by the lines 13 and 14. The 30 liner is then folded up to the general form shown in Figure 7. This forms a rear side portion 15 and a front side portion 16.

When the liner is inserted in the casing, the corner flaps are folded against the side portions 15 and 16. This forms 35 the liner to a rectangular shape of a size to fit into the container. It will be noted that the rear portion 15 is wider than the front portion 16. When folded up, this allows a flap 17 (see also Figure 2). This flap extends along the closure 6 and closes the liner when the cover 6 is closed.

40 This flap may be made wide enough to provide overlap so that a complete seal is attained adapted to protect the contents of the container from 45 drying out.

50 It will be seen that this invention accomplishes its objects in providing a container which may be made up in a flat form, conveniently carried in the pocket and which, when opened, will auto- 55

matically expand. Upon expansion sufficient room is provided for inserting the pipe into the container so as to fill it within the container and thereby avoid spilling. The container may be 5 made up of a single sheet of metal without joints at the ends, and, accordingly, a very cheap container may be constructed. The liner within the 10 container is adapted to break joints with the joints in the outside container, thereby rendering it additionally safe against leakage of the 15 contents. The bellows folds 12 are such as to render the liner expandible with the container.

This container may be made of any suitable 15 material and may be used for holding any kind of loose material as well as tobacco. The liner 20 may be made of paper or other suitable material.

The term "loose material," as used in this specification and the appended claims, is intended to 25 designate such material as pipe tobacco as distinguished from caked material or finished objects.

It is obvious that various changes may be made, 25 within the scope of the appended claims, in the details of construction without departing from the spirit of this invention; it is to be understood, therefore, that this invention is not limited to the specific details shown and/or described.

Having thus described the invention, what is 30 claimed is:

1. A container of the character described, comprising, a casing formed of a single piece of sheet material folded to provide stiff enclosing walls, unconnected at the sheet edges but with substantially closed joints adapted to retain loose material, and means rendering said casing expandible for access to the interior thereof.

2. A container of the character described, comprising, a casing formed of a single piece of sheet material folded to provide stiff enclosing walls, unconnected at the sheet edges but with substantially closed joints adapted to retain loose material, means rendering said casing expandible for access to the interior thereof, and a closure for said casing adapted to retain the same in un- 45 expanded condition.

3. A container of the character described, com-

prising, a casing formed of a single piece of sheet material folded to provide stiff enclosing walls, unconnected at the sheet edges but with substantially closed joints adapted to retain loose material, means rendering said casing expandible for access to the interior thereof, and a liner of sheet material within said casing formed to break joints therewith. 5

4. A container for loose materials, comprising, a casing adapted to receive and hold the material and having stiff side walls and end walls, constructed and arranged to form a flat package adapted for carrying in the pocket, said side walls being connected for limited expansion to permit access to the interior of said casing and said end walls being unconnected but with substantially closed joints. 10 15

5. A container for loose materials, comprising, a casing adapted to receive and hold the material and having stiff side walls and end walls, constructed and arranged to form a flat package adapted for carrying in the pocket, said side walls being connected for limited expansion to permit access to the interior of said casing and said end walls being unconnected but with substantially closed joints, a closure for said casing adapted to retain said side walls in collapsed relation, and means operating to expand said walls upon opening said closure. 20 25

6. A container of the character described, comprising, a casing formed of sheet material having stiff enclosing walls unconnected at the sides of said casing but with substantially closed joints adapted to retain loose material, and means rendering said casing expandible for access to the interior thereof. 30 35

7. A container of the character described, comprising, a casing formed of sheet material having stiff enclosing walls unconnected at the sides of said casing but with substantially closed joints adapted to retain loose material, means rendering said casing expandible for access to the interior thereof, and a liner of sheet material formed to break joints therewith. 40 45

EDWIN SHERMAN.
